UNITED STATES PATENT OFFICE

128,972

DESIGN FOR A HANDLE GRIP FOR COOKING VESSELS OR THE LIKE

William A. Welden, Stamford, Conn., assignor to
Revere Copper and Brass Incorporated, Rome,
N. Y., a corporation of Maryland

Application June 24, 1940, Serial No. 93,215

Term of patent 14 years

To all whom it may concern:

Be it known that I, William A. Welden, a citizen of the United States and a resident of Stamford, county of Fairfield, State of Connecticut, have invented a new, original, and ornamental Design for a Handle Grip for Cooking Vessels or the like, of which the following is a specification, reference being had to the accompanying drawing, forming part thereof.

In the drawing:

Fig. 1 is a side elevational view of a handle grip, for cooking vessels or the like, showing my new design, the cooking vessel shown in dotted lines being merely illustrative of the manner in which the handle grip is associated therewith;

Fig. 2 is a side elevational view of the handle grip according to Fig. 1 on an enlarged scale;

Fig. 3 is a top plan view of the handle grip according to Fig. 2;

Fig. 4 is a bottom plan view of the handle grip according to Fig. 2;

Fig. 5 is an end elevational view of the handle grip according to Figs. 1, 2 and 3 as viewed from the left; and

Fig. 6 is an end elevational view of the handle grip according to Figs. 1, 2 and 3 as viewed from the right.

The stippling on the figures of the drawing represents surface shading.

I claim:

The ornamental design for a handle grip for cooking vessels or the like, substantially as shown and described.

WILLIAM A. WELDEN.
